CONTAINER

Thorwald Hansen, Duluth, Minn., assignor of one-half to Ole Gisvold, Minneapolis, Minn.

Application July 27, 1945, Serial No. 607,445

10 Claims. (Cl. 206—37)

1

My present invention relates to containers, and more particularly to small divided or sectional containers, the compartments of which may be separately and selectively opened and closed with ease and by the use of the one hand in which the container is held.

Although there are various uses to which a container of the type disclosed might well be adapted, certain characteristics and features lend it well to the piscatorial field without in any way limiting its adaptations to many and widely varied arts and without departing from the spirit and scope of the invention. For example, and as will be more fully pointed out, the sectional or divided construction, together with other factors, make feasible its manufacture from a thin, light, transparent plastic material admirably suited to use as a pocket size fly box in which fishermen carry a selected assortment of lures. In such an adaptation, the sectional construction, transparency, strength of construction from light material, and the capability of easy and selective opening of the sections with but one hand are salient features.

It is a general object of my present invention to provide a sectional container, the dividing partitions of which serve as reinforcements to rigidify the structure and make feasible its construction from relatively thin, light weight material.

For another object the invention comprehends the provision of a container having a curved outer contour encompassed by an endless closure strip which is slidable to open and close the container.

Another object of my invention is to provide a container adapted to be made wholly or in part of molded or fabricated transparent material.

The invention has for a further object the provision of a sectional container adapted to be held in one hand, and the compartments of which may be selectively opened by movements of the one hand in which it is held.

As an additional object my invention contemplates the provision of a sectional container especially suited to use by fishermen for carrying and making readily accessible under adverse circumstances an assortment of lures, such as flies or the like.

Other objects and advantages of the invention will be apparent from the following description and the accompanying drawings, in which similar characters of reference indicate similar parts throughout the several views.

2

Referring to the drawings of which there are two sheets:

Fig. 1 is a perspective view of a preferred embodiment of my invention, indicating one way in which it is adapted to be held for effective one-handed operation and depicting a size suitable for use as a container for fish lures such as flies;

Fig. 2 is a perspective view of the container shown in Fig. 1 drawn to a larger scale and having parts broken away to show details of the construction;

Figs. 3 and 4 are respectively plan and side sectional views of the container shown in Fig. 2 with the sections taken substantially on lines 3—3 and 4—4 of Fig. 2;

Fig. 5 is a perspective view of a part of the container shown in Figs. 1 to 4 inclusive;

Fig. 6 is a top plan view of a container embodying my invention and illustrating a modification of the container structure;

Fig. 7 is an end sectional view of the container structure shown in Fig. 6 with the section taken substantially on a line 7—7 of Fig. 6;

Fig. 8 is a side elevational view of the container shown in Fig. 6; and

Fig. 9 is an end sectional view similar to Fig. 7 but illustrating another modified type of construction for a container embodying my invention.

In this specification the term "oval" is employed in its broad sense—rather than any strict or mathematical sense—to describe those non-circular closed curvilinear figures of which the ellipse, the side elevation of a football, and the end elevation of a partially flattened cylinder, are common examples.

Referred to Figs. 1 to 5 inclusive of the drawings, the container therein depicted is illustrated as being of a size and construction particularly suited to the carrying of assorted flies by fishermen for ready access while fishing. Although a container of the type shown might be made of various materials, the disclosed embodiment is

preferably constructed of a transparent plastic material with the parts cemented together. Several features which are attributable to the disclosed construction, particularly when made of a transparent plastic, are that it is light, strong, durable, will float if it is dropped into the water, the contents may be scrutinized without opening the container, the closure element or cover is easily manipulated by one-hand operation for selective opening, and it does not involve any

55 complex or mechanical parts which are subject

to wear or may get out of order and thereby cause unexpected difficulties.

In the disclosed embodiment the container 10 has substantially oval shaped ends 12 and 13 which in the fabricated construction are flat or plane and are disposed in spaced parallel relationship with their longitudinal axes lying in a common plane. By preference the ends 12 and 13 and the intermediate partition 14 are sufficiently thick to provide substantial rigidity to the structure. Extending laterally in relatively spaced relationship and spaced inwardly from the ends of the intermediate partition are lateral partitioning elements 15, 16, 17 and 18. Opposite ends of the partitioning elements 15, 16, 17 and 18 are cemented to the ends 12 and 13 of the container and to the intermediate partition 14. The other edges of the partitioning elements are desirably flush with the opposite longitudinal edges of the intermediate partition 14 at their positions of abutment therewith. Thus, the lateral partitioning elements determine the relative spacing of the ends 12 and 13 with respect to the intermediate partition 14 and brace those parts of the container structure, as well as coacting with the intermediate partition to divide the space between the container ends into compartments.

In the preferred construction the ends 12 and 13 are of the same size and shape while the intermediate partition is similar in shape but smaller than the ends by a uniform marginal amount. An inner covering wall 19 encompasses the intermediate longitudinal partition 14, extends across the lateral partitioning elements, and extends laterally between the ends 12 and 13 with its opposite edges abutting those ends. This inner covering wall is secured by cementing or other suitable means to the intermediate partition, the lateral partitioning elements, and the inner surfaces of the container ends. In alignment with each of the compartments separated by the intermediate partition and lateral partitioning elements, the inner covering wall has an access opening 20, all of which openings are desirably in one face of the container.

At the outer edges of the outer surface of the inner covering wall 19, flange or edge strips 22 overlie the inner covering wall adjacent the ends 12 and 13 and extend inwardly a short distance in substantially flush relationship to the edges of the ends and are secured by cementing to both the ends and the inner covering wall. These edge or flange strips 22, together with the outer surface of the inner covering wall 19, define a relatively shallow channel in which a flexible belt-like outer cover 23 is mounted for longitudinal sliding movement relative to the ends and the inner covering wall.

For selectively opening single compartments of the container one at a time, two laterally and longitudinally spaced openings 24 and 25 are provided in the belt-like outer cover 23. The opening 24 is disposed for successive alignment with the openings 20 on one side of the longitudinal partition 14 while the opening 25 is disposed for successive alignment with the openings 20 on the other side of the longitudinal partition. With the preferred longitudinal separation of the openings 24 and 25, they are at relatively opposite longitudinal positions with respect to the inner covering wall 19 of the container. All of the openings 20 are closed when the openings 24 and 25 in the belt-like cover are at opposite ends, and the

compartments of each row may be opened singly and separately.

As depicted in Fig. 1, a container of the type disclosed, when made in the proper size, may be held in one hand with the thumb and fingers gripping opposite sides of the container along the opposite edges of the intermediate longitudinal partition 14. With the container thus held the hand very well may be moved, while and by squeezing the container, in a manner such that the thumb moves in one direction along one side while the fingertips move in the opposite direction along the other side; and this relative movement of the thumb and fingers carries with it the flexible belt-like outer cover to move that cover to a position in which a desired one of the openings 24 or 25 therein is aligned with a selected opening 20 so as to provide access to the desired compartment of the container. Collapse of the container by the squeeze of the relatively moving thumb and fingers effectively is prevented by the intermediate longitudinal partition 14 which in turn derives adequate lateral support from the cross partitions 15, 16, 17 and 18. Thus, its generally oval shape not only makes the container easy to carry in the pocket and easy to grip in the hand, but also stabilizes the position of the stationary parts of the container while the belt-like outer cover moves under finger manipulation.

If the container is constructed entirely of transparent plastic material, as is particularly desirable when it is utilized as a fly box, any desired fly may be pre-selected with the box closed and then obtained without difficulty by the described one-handed operation of the box.

The general structure and operation of the forms shown in Figs. 6, 7 and 8 are quite similar to those of the described form which is illustrated in Figs. 1 to 5 inclusive. However, the structure of this modified form is adapted to the integral molding of two similar and opposite halves 26 and 27 which part at a longitudinal central plane along the intermediate partition 14 and are secured together by fastening means such as cross screws 28 at opposite ends of the container. Considering the structure of the halves 26 and 27 of the container housing in more detail, ends 29 and 30 are molded integrally with the projecting halves of the inner covering wall 19. The ends 29 and 30 may be bowed outwardly and they desirably have at their outer edge adjacent the inner wall 19 an integrally formed peripheral flange 32 recessed at 33 to serve as a guide for one edge of the flexible belt-like outer cover 23. The inner surfaces of the inner wall 19 are grooved to provide shoulders 34 which abut and retain the intermediate partition 14 when the two halves are secured together. The lateral partitioning elements 15, 16, 17 and 18 are integrally formed with their respective ends and halves of the inner wall and abut the intermediate partition when assembled. When adapted to be secured together by fastening means such as the illustrated cross screws 28, each of the halves has an end portion 35 of increased section through which extends a lateral opening 36 for the accommodation of the screw. One of the halves of each associated pair has one end of the opening threaded as at 37 while the other half is countersunk to accommodate the head of the screw.

Although either of the forms thus far described is adapted to be carried in a pocket, it is also within the purview of the invention to provide

means by which the container may be connected to a suitable cord and hung around the neck of the user. As shown in Figs. 6 and 8, an integrally formed projecting lug 39 at one end of each of the halves has a transverse opening 40 therethrough for the accommodation of the cord.

The belt-like outer cover utilized with the form of container shown in Figs. 6 to 8 inclusive is desirably similar to that shown in Fig. 5. Likewise, the access openings 20 in the inner wall 19 are aligned with each of the compartments and bear a relation similar to that described with respect to the openings 24 and 25 in the belt-like outer cover.

In the assembly of the container shown in Figs. 6 to 8 inclusive, the belt-like outer cover and intermediate partition are placed in position on one of the halves after which the other half is placed and secured in position relative thereto.

Like the form shown in Figs. 6 to 8 inclusive, that shown in Fig. 9 is adapted to the integral molding of some of the parts. In this form, however, the inner covering wall 19 is integrally molded with the longitudinal intermediate partition 14 and also the lateral partitioning elements 15 and 16. Thus, the ends of the compartments open outwardly and oppositely and are covered by separately molded ends 42 and 43. The inner edges of the ends 42 and 43 are peripherally recessed to provide shoulders 44 against which the outer edges of the inner wall 19 are held in the assembly and which are sufficiently large to provide recesses for guiding the belt-like outer cover 23.

The ends 42 and 43 are held in assembled relation relative to the integrally formed inner covering wall and partitions in a manner similar to that described with respect to the form shown in Figs. 6 to 8 inclusive. In this form the molded ends desirably include partitioning elements such as 45 which align with and abut the outer ends of the lateral partitioning elements such as 15 and 16 in the assembly in order to complete the separation of the compartments.

My concept of an ideal fly box is one which is not too large, is light in weight, conveniently may be carried in the pocket or suspended from the neck, may be opened and closed with one hand, enables the identification of a to-be-selected fly with the box closed, exposes one compartment only at a time, floats if dropped into the water, is sufficiently strong that it will not break if the angler falls on it, and is free from metal parts or springs to get out of order. The present invention provides such a fly box.

Having thus illustrated and described my invention, what I claim as new and desire to secure by Letters Patent of the United States is:

1. A container comprising, in combination, substantially oval shaped ends, a substantially oval shaped intermediate partition smaller than said ends by a uniform marginal amount the longitudinal axes of said ends and intermediate partition being parallel and lying in a plane, cross partitions spaced apart and spaced inwardly from the ends of said intermediate partition, said cross partitions extending from the intermediate partition to the ends in substantially parallel relationship to one another and substantially perpendicular to said longitudinal axes, the edges of said cross partitions being substantially flush with the edges of said intermediate partition, an inner covering wall circumscribing the edges of said partitions and extending laterally between said ends, said inner cover-

ing wall closing the space between said partitions and ends, on one side thereof to form compartments and having openings therein on the other side of the partitions for access to the compartments, and a flexible and endless outer belt-like cover encompassing said inner covering wall and extending laterally between said ends, said outer belt-like cover being slidable around the inner covering wall and having spaced openings therein adapted singly and selectively to align with the openings in the inner covering wall to open said compartments for access when the outer cover is moved.

2. A container comprising, in combination, substantially oval shaped ends and an intermediate partition disposed in substantially parallel relationship to one another with their longitudinal axes in a common plane, said intermediate partition being smaller than said ends by a uniform marginal amount and dividing the space between said ends into two sections, lateral partitioning means substantially perpendicular to said longitudinal axes and to said intermediate partition disposed between the ends of said intermediate partition for dividing at least one of said sections into compartments, said partitioning means having edges flush with opposite edges of the intermediate partition, an inner covering wall circumscribing the edges of the intermediate partition and partitioning means and extending between said ends to cover said sections, said inner covering wall having spaced openings therein providing access to each of the sections and compartments separated by the partitioning means and intermediate partition, and a flexible and endless belt-like cover encompassing and slidable around said inner covering wall, said belt-like cover extending laterally between the ends and having spaced openings therein adapted to align with the openings in the inner covering wall as the endless belt-like cover is moved relative to the inner covering wall.

3. A container comprising, in combination, housing means including substantially oval shaped ends and transversely disposed partitioning means including an oval shaped longitudinal partitioning element defining two rows of compartments, and an inner covering wall encompassing said compartments peripherally of the longitudinal partitioning element laterally between said ends and having therein access openings for each of the defined compartments, an endless belt-like outer cover encircling and slidable relative to the inner covering wall longitudinally of said ends, said belt-like outer cover having longitudinally and laterally displaced openings therein adapted selectively to align with the openings in the inner covering wall during movement of the belt-like outer cover.

4. A container comprising, in combination, housing means including substantially oval shaped ends and transversely disposed partitioning means including an oval shaped longitudinal partitioning element defining two rows of compartments, and an inner covering wall encompassing said compartments peripherally of the longitudinal partitioning element laterally between said ends and having therein access openings for each of the defined compartments, an endless belt-like outer cover encircling and slidable relative to the inner covering wall longitudinally of said ends, said belt-like outer cover having longitudinally and laterally displaced openings therein adapted selectively to align with the openings in the inner covering wall during

movement of the belt-like outer cover, said container being of a size adapted to be gripped in one hand with one of said ends adjacent the palm of the hand and the fingers and thumb gripping opposite surfaces of the outer cover in substantial alignment with the longitudinal partitioning element.

5. A sectionalized container adapted to be made of transparent sheet plastic material and comprising substantially oval shaped end pieces and an intermediate partition disposed in parallel relationship, lateral partitions cemented at opposite ends to one of the end pieces and the intermediate partition and having edges flush with opposite edges of the intermediate partition, an inner covering wall encompassing and cemented to the intermediate and lateral partitions and extending laterally between said ends and cemented thereto, said inner covering wall having access openings therein on opposite sides of each of said partitions, and a flexible belt-like outer cover encircling and slidable relative to the inner covering wall longitudinally of the end pieces, said outer cover normally covering all of the openings in the inner covering wall and having laterally and longitudinally spaced openings therein adapted singly to align with the openings in the inner covering wall during movement of the outer cover.

6. A sectionalized container comprising a pair of moulded and oppositely disposed side portions each including an oval shaped end, an integral oval shaped shell projecting laterally outwardly from one side of the end, said end having an outer flange adjacent the outer surface of the shell, spaced partitions intermediate the ends of said shell and perpendicular to the longitudinal axis of said end, said shell having access openings therein disposed in a row and on opposite sides of each of said partitions, an intermediate longitudinal partition, means holding said side portions together in oppositely disposed relation against the intermediate partition to define two rows of compartments between said ends and on opposite sides of the longitudinal partition, said shells and said outer flanges defining a channel, and a flexible belt-like cover slidable in said channel relative to the shells and having openings therein adapted selectively to align with said access openings upon movement of the belt-like cover.

7. A sectionalized container comprising a pair

of oppositely disposed and similar end covers of substantially oval shape and a sectionalized intermediate part including integrally molded walls defining rows of separate compartments on opposite sides of a longitudinal partition and opening outwardly in opposite directions, rows of access apertures in said intermediate part opening into said separate compartments on opposite sides of said longitudinal partition, means holding said end covers against opposite sides of the intermediate part to cover the outwardly opening ends of said compartments, said end covers having outer edge flanges defining a channel with said intermediate part, and a flexible belt-like cover encircling the intermediate part and slideable in said channel longitudinally of the ends, said belt-like cover being adapted to cover all of said access apertures at one time and having openings therein adapted to align with said apertures during movement of the cover.

8. A fly box or other multi-compartment container, capable of one-hand manipulation to open and close its compartments, comprising: a pair of spaced apart aligned oval end walls, an inner side wall extending around and between the opposed peripheries of said end walls, an intermediate oval wall lying between the end walls and circumscribed by the inner side wall, a plurality of cross walls extending between the intermediate wall and each end wall to define a plurality of compartments, openings in said inner wall through which access may be had to the several compartments, and an outer side wall in the form of a belt lying between the end walls and movable around and in immediate proximity to the inner side wall, said outer side wall having openings that are carried into and out of registry with said access openings when the outer side wall moves circumferentially with respect to the inner side wall under squeezing pressure that tends to flatten said side walls but is resisted by said intermediate wall and said cross walls.

9. An article as specified in claim 8 in which the recited elements are formed of a substantially transparent plastic material.

10. An article as specified in claim 8 in which the end walls and the inner side wall define a shallow endless channel in which the outer side wall lies and moves.
